ELECTROMAGNETIC STEP-BY-STEP MECHANISM.

1,381,514.

Specification of Letters Patent. Patented June 14, 1921.

Application filed September 29, 1919. Serial No. 327,123.

To all whom it may concern:

Be it known that we, CHARLES P. SOPER and JOHN A. HALL, citizens of the United States, residing at Maplewood, in the county 5 of Essex and State of New Jersey, and at Bayside, Long Island, in the county of Queens and State of New York, respectively, have invented certain new and useful Improvements in Electromagnetic Step- 10 by-Step Mechanisms, of which the following is a full, clear, concise, and exact description.

This invention relates to electromagnetic step-by-step mechanisms and more particularly to means for electrically controlling the operation of such mechanisms.

The object of the invention is to provide an improved step-by-step mechanism in which the full step both forward and backward is insured, not by any mechanical adjustment of springs, but rather by the movement of the member to be moved.

Heretofore in such arrangements the movement of the actuating member has been controlled by mechanical means which although adjusted to correspond with the movement of the member to be moved, nevertheless did not coöperate with it. According to the above object the present invention 25 contemplates an arrangement wherein no special adjustment is necessary since the movement of the actuating member is controlled by the movement of the actuated member.

More specifically this invention comprises a magnetically actuated pawl adapted to step a ratchet member forward, and a holding pawl adapted to prevent backward movement of said ratchet member. Each of 35 these pawls controls contacts in the energizing circuit of the electromagnet, said contacts being so arranged that on the forward movement of the ratchet member the circuit arrangement is maintained undisturbed until the holding pawl drops into a succeeding tooth at the end of a step. Thereupon the condition of the circuit is changed and this changed condition is maintained until the stepping pawl drops into a succeeding tooth at which time the mechanism 45 is ready to repeat this cycle of operations. Any desired means for closing the electrical circuit to initiate stepping and opening it to arrest stepping may be provided. The

mechanism may be employed to rotate a 5 shaft, to advance a toothed bar, or wherever a step-by-step movement is desired.

In the drawings Figure 1 is a view in elevation of the invention applied to a mechanism in which an electromagnet in attracting its armature actuates a pawl to step a ratchet wheel, and in retracting its armature moves the pawl into engagement with a succeeding tooth preparatory to the next step. Fig. 2 is a view in elevation of the 60 invention applied to a mechanism in which an electromagnet in attracting its armature moves a pawl backward to engage a tooth of a ratchet wheel, and in retracting its armature actuates the pawl to step the ratchet 65 wheel forward.

Both Figs. 1 and 2 show the mechanisms in normal position with the electromagnets deenergized. The circuits for the electromagnets are indicated diagrammatically. 75 Fig. 3 shows a portion of the mechanism illustrated in Fig. 2 at the moment just before the armature is completely attracted and as the stepping pawl is about to engage a new tooth.

Referring more particularly to Fig. 1, an electromagnet 1 is secured to a yoke 2 upon which is pivotally supported an armature 3, at the point 4. Contact springs 5, 6, 7 and 8 are mounted upon a bent over portion 9 of the yoke 2, being insulated therefrom and from each other in any desired manner. A spring 10 retracts the armature 3 when the magnet 1 is deenergized, the retracting movement being arrested by a stop 11 fixed 80 to the frame (not shown). A stepping pawl is pivotally mounted at the end 12 of armature 3. The pawl 13 is held in engagement with the teeth of a ratchet wheel 14 by the pressure of spring 8 on a button 18 of insulating material rigidly fixed to pawl 13. The ratchet wheel is rigidly mounted on a shaft 15 which may be rotatably supported in any desired manner. Backward movement of wheel 14 is prevented by the end 17 85 of spring 5 which acts as a holding pawl.

When the switch 16 is closed, a circuit is completed to energize magnet 1, which circuit may be traced from grounded battery, switch 16, through the winding of magnet 105 1, springs 8 and 7 to ground. Magnet 1 in attracting its armature actuates pawl 13 to step ratchet wheel 14 forward, that is

in a clockwise direction. Near the beginning of the step, spring 5 is forced by the tooth upon which its holding portion 17 has been resting, into engagement with spring 5, thus completing a substitute energizing circuit for magnet 1 which may be traced through springs 5 and 6 in parallel with the circuits previously traced through springs 7 and 8. Just after the closure of springs 5 and 6, the button 18 carried by pawl 13 encounters a bent portion 19 of spring 8, thus forcing springs 7 and 8 apart. The button 18 is so positioned that it will hold springs 7 and 8 apart throughout the remainder of the forward step of pawl 13. The magnet thus remains energized until the holding end 17 of spring 5 passes over the edge of the tooth upon which it has been riding and drops into engagement with the next tooth. In dropping into engagement with the next tooth, spring 5 opens the circuit for magnet 1 at the contact between springs 5 and 6, and magnet 1 de-energizes, its armature 3 being retracted under the tension of spring 10 until it encounters stop 11.

During the retraction of armature 3, springs 7 and 8 are held apart by the engagement of button 18 with spring 8 until pawl 13, in dropping into engagement with the next tooth, again closes the contact between springs 7 and 8, whereupon the cycle of operations described is repeated. Thus stepping continues as long as switch 16 remains closed.

In the mechanism shown in Fig. 2, a magnet 20 is secured to a frame member 21, on which is pivotally mounted at 22 an armature 23. Armature 23 is normally held in retracted position against a stop 24 by spring 25. A lever 26 rigidly mounted on armature 23 pivotally supports at 27 a crank-shaped stepping pawl 28. Contact springs 29, 30, 31 and 32 are secured to frame piece 21 by a screw 37 and are insulated therefrom and from each other. Pawl 28 is held in engagement with the teeth of a ratchet wheel 34 by the pressure of spring 29 on the arm 33, and the pressure of the teeth on the nose of pawl 28 causes arm 33 to close the contact between springs 29 and 30 at all times except that just after pawl 28 has ridden over the edge of a tooth and has dropped into engagement with the next tooth. The ratchet wheel 34 is rigidly secured to a shaft 35 which is rotatably mounted in any desired manner. Spring 31 acts as a holding pawl, and is positioned so as to make contact with spring 32 only in the position which it occupies just after spring 31 has ridden over the edge of a tooth. In other positions the pressure of the tooth moving under spring 31 forces it away from spring 32 so as to break their contact.

When switch 36 is closed, a circuit is com-

pleted from grounded battery, switch 36, through contact springs 29, 30, 31 and 32, in series, through the winding of magnet 20 to ground. Magnet 20 is energized in this circuit and attracts its armature 23. Throughout the attractive step of armature 23 the nose of the pawl 28 is forced upward by the tooth over which it is passing, thereby holding arm 33 against spring 29 to maintain the closed condition of the contacts between springs 29 and 30. As the wheel 34 is not in motion during this step, springs 31 and 32 remain in contact. Fig. 3 shows the position of the pawls and contact springs near the end of the attractive step of armature 23. Thus the energizing circuit for magnet 20 is maintained until the pawl 28 in dropping into engagement with the next tooth allows spring 29 to give a clockwise rotation to the pawl 28, thereby opening the contact between springs 29 and 30. The energizing circuit being thus broken, magnet 20 de-energizes and its armature 23 is retracted by spring 25. During this retractive movement pawl 28 is moved to the right by lever 26 to step the wheel 34 in a clockwise direction. Spring 31 in riding over the tooth with which it is in engagement, opens the contact between springs 31 and 32, so that the energizing circuit of magnet 20 is maintained open at this point until spring 31 drops into engagement with the next tooth. At this time pawl 28 has completed its forward step and closed the contact between springs 29 and 30 so that the circuit is again completed for energizing magnet 20, and this cycle of operations continues as long as switch 36 is closed.

Thus it will be seen that in both the types of mechanism illustrated in Fig. 1, and in Fig. 2, the magnet circuit is changed to cause a forward step of the ratchet wheel when the stepping pawl passes over the edge of one tooth to drop into engagement with a new tooth, and that this condition of the circuit is maintained through the forward step until the holding pawl passes over the edge of one tooth and drops into engagement with a succeeding tooth. In each case the dropping of the holding pawl into engagement with the succeeding tooth changes the condition of the circuit to cause backward movement of the stepping pawl preparatory to the next step.

What is claimed is:

1. In an electromagnetic step-by-step mechanism, a ratchet member, means for stepping said ratchet member forward, an electromagnetic means for operating said stepping means, mechanical means actuated when said electromagnetic means is rendered inoperative to restore said stepping means to normal position, means for holding said ratchet member after it has been stepped forward, means actuated by said stepping

means in dropping into engagement with a ratchet tooth to actuate said electromagnetic operating means, and means actuated by said holding means in dropping into engagement with a ratchet tooth to render inoperative said electromagnetic means.

2. In an electromagnetic stepping device, a ratchet member, a pawl to step said ratchet member, a pawl to hold said ratchet member after it has been stepped, a magnet to operate said stepping pawl, a spring to restore said stepping pawl, an energizing circuit for said magnet, means actuated by said stepping pawl when it drops into engagement with a ratchet tooth to complete said energizing circuit, and means operated by said holding pawl when it drops into engagement with a ratchet tooth to break said energizing circuit to allow said spring to move said stepping pawl into engagement with a fresh tooth.

3. In an electromagnetic stepping device, a ratchet member, a pawl to step said ratchet member, a pawl to hold said ratchet member after it has been stepped, a magnet to operate said stepping pawl, a spring to restore said stepping pawl, an energizing circuit for said magnet, a contact member actuated by said stepping pawl when it drops into engagement with a ratchet tooth to complete said energizing circuit, and a second contact member operated by said holding pawl when it drops into engagement with a ratchet tooth to break said energizing circuit to allow said spring to move said stepping pawl into engagement with a fresh tooth. 25 30 35

In witness whereof, we hereunto subscribe our names this 23rd day of September, A. D. 1919.

CHARLES P. SOPER.
JOHN A. HALL.
